UNITED STATES PATENT OFFICE.

THOMPS ROBINS RICHEY, OF ATLANTA, TEXAS.

HIGHWAY SAFETY DEVICE.

Application filed May 4, 1925. Serial No. 27,811.

My invention relates to a highway safety device especially adapted to prevent accidents at railway crossings.

The object of my invention is to provide a safety device which will insure careful driving at railroad crossings. My device contemplates forcing the vehicle-driver to slow down at crossings to a slow rate of speed so that ample opportunity may be afforded to discover that a train is approaching. In addition, the device is so constructed as to serve as a forcible reminder that the railroad tracks are near.

I am aware that the use of various safety devices at highway crossings has been proposed but none of them have, it appears, come into practical or successful use. The main reason which may be assigned for the failure of the safety devices which have been proposed is their complexity and lack of durability.

My device eliminates these defects, being simple in structure, durable and low in initial cost. I propose to anchor in the highway transversely thereof, on both sides of the railway track, at a suitable distance therefrom, a protruding element such as a log, preferably a solid concrete log. The presence thereof will usually be noted by the vehicle-driver as he approaches the crossing causing him to slow down but if he is absent-minded, as is frequently the case, as he passes over the protruding element or mass the vehicle will be jolted and the vibrations will be transmitted to the driver notifying and reminding him that it is necessary to slow down.

In the drawing which embodies my invention in its preferred form, Fig. 1 is a perspective view showing concrete logs anchored in the highway transversely thereof on both sides of the railway track;

Fig. 2 is a perspective view of the log itself;

Fig. 3 is a cross-sectional view showing the log embedded or anchored in the road;

Fig. 4 is a cross-sectional modification in which the safety device is integral with the highway, and

Figs. 5, 6 and 7 are cross-sectional views of logs having iron cappings of different types.

The highway 1 is crossed by the railway track 2. At a suitable distance from each

rail 3 of the track 2, there is anchored in the highway a log, preferably a concrete log 4. Each log protrudes a suitable distance above the highway and may be formed in the shape of a half cylinder thereby providing receding shoulders 5. Each log at its uppermost portion 6 may protrude above the highway any suitable distance for example, six or seven inches. Each log 4 is anchored or embedded in the highway for a distance of about four inches. In this manner the portions of the shoulders 6 adjacent the highway will be protected from breaking due to heavy traffic.

In Fig. 4, the concrete log is shown integral with the highway being formed as the highway is built. This is advantageous in that there is no difficulty in securing a permanent junction between the log 4 and the highway 1. Additionally, this construction is advantageous in that the first cost is greatly reduced.

In the modification shown in Fig. 5, the log 7 is capped with an iron capping 8 provided with a flange 9 embedded in concrete. The capping may be an iron alloy for example, one containing vanadium which is well known to be a great strengthener of steel, acting in a large measure against dynamic strains. In Fig. 6, the capping 10 is provided with flanges 11, which serve to effectively anchor the capping. In Fig. 7, the capping 11 extends around the edges of the log 12 which are adjacent to the highway 1, as at 13, and additionally, is provided with a central flange 14. The bolt 15 passing through the flanges 13 and 14 acts in conjunction therewith as a reinforcement. It is obvious that in the constructions shown in Figures 5, 6 and 7, the concrete log may be integral with the highway and the iron capping can be set in place at the time the highway and the protruding log are initially made.

Instead of making the log of concrete or with a metal capping, the entire log may be composed of solid metal or of hollow metal. In the latter case, the metal must be one adapted to withstand great dynamic strains.

The log may and usually does stretch transversely across the entire highway. Obviously, the width of the log may vary but one thirty inches wide has given satisfactory results.

The logs may advantageously be placed on each side of the crossing at a distance of about thirty feet therefrom.

I claim:

- 5 1. The combination with a highway crossing, of a highway provided with a protruding element on each side of the crossing and extending transversely of the entire highway, at a sufficient distance from the crossing to cause an approaching vehicle-driver to slow down before the crossing is reached.
- 10 2. The combination with a highway crossing, of a highway provided with a protruding concrete log on each side of the crossing and extending transversely of the highway, at a sufficient distance from the crossing to cause an approaching vehicle driver to slow down before the crossing is reached.
- 15 3. The combination with a highway crossing, of a highway provided with a protruding concrete log on each side of the crossing and extending transversely of the entire highway, at a sufficient distance from the crossing to cause an approaching vehicle-driver to slow down before the crossing is reached.
- 20 4. The combination with a highway crossing, of a highway provided with a protruding concrete log in the shape of a half cylinder on each side of the crossing and extending transversely of the entire highway, at a sufficient distance from the crossing to cause an approaching vehicle-driver to slow down before the crossing is reached.
- 25 5. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping provided with flanges at the edges of the concrete base adjacent to the highway.
- 30 6. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping provided with a central flange and side flanges, the capping being tied to the concrete base by a transverse member extending through said flanges.
- 35 7. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping permanently attached to the concrete and resistant to dynamic strains.
- 40 8. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping made of an iron vanadium alloy and resistant to dynamic strains.
- 45 9. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping provided with flanges at the edges of the concrete base adjacent to the highway.
- 50 10. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal capping provided with a central flange and side flanges, the capping being tied to the concrete base by a transverse member extending through said flanges.
- 55 11. The combination with a highway crossing, of a highway provided with a protruding element on each side of the crossing embedded in and extending transversely of the highway, at a sufficient distance from the crossing to cause an approaching vehicle-driver to slow down before the crossing is reached, said protruding element being composed of a concrete base and a metal-alloy capping provided with a central flange and side flanges, the capping being tied to the concrete base by a transverse member extending through said flanges.
- 60 12. As a new article of manufacture, a safety device adapted to extend transversely of a highway at a predetermined distance from the highway crossing comprising a shaped concrete member provided with a permanent metal capping.

In testimony whereof he hereunto affixes his signature.
